TILTING CHAIR

Willem van Osselen, Huis ter Heide (Utrecht),
Netherlands, assignor to Gispen's Fabriek voor
Metaalbewerking N. V., Rotterdam, Netherlands

Application October 2, 1950, Serial No. 187,878
In the Netherlands February 22, 1950

1 Claim. (Cl. 155—77)

1

My present invention relates to chairs of the type wherein the seat is pivotally mounted, at or close to its front edge, upon a base member and adapted to be held by a spring member in normal, substantially horizontal position, said spring member being loaded when the seat is depressed so as to swing about its pivot.

It is desirable that chairs of this kind be of a character such that the seat is held in normal, i. e. unoccupied, substantially horizontal position as long as the person using the chair is sitting on the same in the normal and usual way, but that it is readily and smoothly tilted or tipped against the action of the spring member when said person shifts his center of gravity rearwards to lean back, so that the comfort of the person is best provided for.

In accordance with the present invention a chair, comprising in combination a base member, a seat pivoted to the base member about a cross axis close to its front edge, and a spring member tending to hold the seat substantially horizontal, is provided with at least one arm whose lower end is rotatably mounted upon the base member about an axis in parallel relation with the pivot of the seat and whose upper end is urged by the spring member into supporting engagement with the seat so as to assume a position wherein it has only a slight rearward deviation from the vertical when the seat is substantially horizontal, an abutment being provided preventing the arm from being moved by said spring member in forward direction beyond said position.

In order that my invention may be more fully understood by those skilled in the art, I shall now proceed to describe a preferred embodiment thereof with reference to the annexed drawing, in which:

Fig. 1 is a plan view of the base member of the chair,

Fig. 2 is a side elevational view of part of the base member and the seat, and

Fig. 3 is a somewhat diagrammatic side view, on a reduced scale, of the complete chair with a rearwardly leaning person sitting thereon.

As shown, the chair comprises a base member 4 supported by four casters 5 and accommodating a central, vertical spindle 6. Rigidly secured to the top end of spindle 6 is a cross-piece 7, to whose ends are rigidly secured two parallel supporting bars 8, 9 of equal lengths and extending in forward direction. The offset ends of said bars are interconnected by a cross rod 10 rotatably supported in suitable bearings thereof.

Rod 10, in combination with two rearwardly extending bars 11, 12 rigidly secured thereto, constitute the tiltable frame for supporting the seat 13 and the back 14 of the chair.

5 Hinged to the bars 8, 9 in points spaced a small distance from the cross-piece 7 are arms 15, 16 adapted to swing about aligned axes parallel with rod 10. Each of said arms is provided, in addition to a roller 15a (16a) pivoted thereto near its upper end and rotatable relative thereto about an axis parallel with rod 10, with a hook 15b (16b) at its upper end and, intermediate its lower end and its roller, with a lug 15c (16c) engaged by one end of a coiled spring 17 (18), the other end of which is secured to a screw 19 (20) extending through a hole of bar 8 (9). The projecting end of said screw is in threaded engagement with a nut 21 (22) having a milled head.

20 By means of nuts 21, 22 the springs 17, 18 can be tensioned so that the arms 15, 16, through their rollers 15a, 16a, are urged into engagement with the lower edges of bars 11, 12 and thereby tend to swing the seat upwards about its pivot 10. However, when the seat assumes its normal, substantially horizontal position the hooks 15b, 16b of said arms engage abutments 11a, 12a provided on bars 11, 12, thus positively preventing the seat from swinging upwards beyond normal position.

25 In Fig. 2, the seat in normal position is shown in full lines. If, now, a person sits down in the chair in the usual way, the seat remains substantially horizontal, provided the springs 17, 18, have been suitably tensioned in accordance with the weight of said person. Since, in this position of the seat, the arms 15, 16 are almost vertical, it is obvious that the pull exerted by said springs on said arms need only be comparatively slight. However, if said person shifts his center of gravity rearwards by leaning back, the load on the springs will be increased until the resisting moment exerted on the arms 15, 16 by the springs equals that exerted by the load, whereupon any further rearward displacement of said center of gravity will cause the seat to tilt and to reach another position of equilibrium (as shown in dotted lines in Fig. 2), whereby the arms 15, 16 are swung backwards and the springs 17, 18 are further tensioned. Owing to said swinging movement of arms 15, 16, the increase of the moment exerted on the arms 15, 16 by the load on the seat is comparatively very rapid, so that the tilting movement of the seat is 50 smooth and comfortable. During this tilting

55

movement the front edge of the seat remains on the same level, thus allowing the person leaning back in the chair to comfortably rest with his feet on the floor as shown in Fig. 3.

If the person thereafter resumes normal position, the seat will immediately follow.

What I claim is:

A tilting chair comprising a base member, a seat having a front edge and pivotally mounted adjacent said front edge on said base member for swinging about a horizontal cross axis, a back rest rigidly secured to said seat, at least one upwardly directed arm pivotally mounted at its lower end on said base member for swinging about an axis spaced rearwardly from said front edge and in a vertical plane disposed at right angles to said horizontal cross axis, a spring member interconnecting said base member with said arm to resiliently urge the latter in the direction towards said front edge of the seat, 20

means limiting the spring urged movement of said arm to a position in which said arm has only a slight rearward deviation from the vertical, and means on said arm operative to support said seat during the rearward swinging movement of said arm, the last mentioned means being positioned on said arm so that said seat is substantially horizontal when said arm is in said limited position.

WILLEM VAN OSSELEN.
